UNITED STATES PATENT OFFICE.

FRANK L. SLAZENGER, OF NEW YORK, N. Y.

GOLF CLUB.

Application filed May 5, 1925. Serial No. 28,196.

To all whom it may concern:

Be it known that I, FRANK L. SLAZENGER, a citizen of United States, residing at New York city, in the county of New York and State of New York, have invented certain new and useful Improvements in Golf Clubs, of which the following is a specification, reference being had therein to the accompanying drawing.

10 The present invention relates to golf clubs, and aims to provide novel and improved means for anchoring or securing a metal shaft in the club head, in order to provide for a secure and rigid connection and one 15 that will, if the glue or cement loosens, still remain tight to prevent the head flying off the shaft.

Resilient tubular metal shafts are rapidly becoming the vogue, and the demand for 20 them is increasing. One objection to the use of a metal shaft is the difficulty in securing the shaft to the head so as to withstand the severe shocks and strains to which the club 25 is subjected in use. The present invention contemplates the provision of simple and effective means for securing a metal shaft in the head, and even though glue or cement used may loosen, the head will remain tightly on the shaft, the impact of the head with 30 the ball serving to tighten the head on the shaft.

With the foregoing and other objects in view, which will be apparent as the description proceeds, the invention resides in 35 the construction and arrangement of parts, as hereinafter described and claimed, it being understood that changes can be made within the scope of what is claimed, without departing from the spirit of the invention.

40 The invention is illustrated in the accompanying drawing, wherein—

Figure 1 is a front view of the head end of a golf club embodying the improvements.

45 Fig. 2 is a median vertical section through the joint between the head and shaft.

The head 7 is of wood, as usual, and may be of any suitable size and shape, being provided with the inclined shank 8, and the 50 striking face 9. The shank 8 has a tapered bore or socket 10 extending to a point behind the heel end of the face 9 to receive the shaft 11. The shaft 11 is of steel or other suitable metal, so as to be resilient, and is 55 tubular.

In order to secure the shaft in the head,

a sleeve 12 of aluminum or other suitable metal or alloy is cast on the lower terminal portion of the shaft 11, so as to be intimately united with the shaft substantially 60 integral therewith. The sleeve 12 is tapered slightly from a point near its upper end to its lower end to conform to the downward taper of the socket 10, so that said sleeve will wedge tightly into the socket. The 65 upper terminal 13 of the sleeve is tapered off upwardly so as to provide a neat finish.

The lower terminal portion of the sleeve 12 is formed with a screw-thread 14 so as to screw into the wood of the head within 70 the lower portion of the socket 10. The sleeve 12 projects sufficiently from the shank 8 so that it may be engaged by a wrench, vise or other implement when securing the sleeve 12 into the head. Glue or cement is 75 used between the sleeve 12 and head, as usual, in order to obtain adhesion between the head and shank.

The screw-thread 14 extends in such a direction that if the glue or cement between 80 the sleeve 12 and shank 8 becomes loose, the tendency for the head 7 to rotate around the shank due to the impact of the head against the golf ball, will screw the head 85 tighter on the shank. Thus, the greater the impact the tighter will the head be screwed on the shaft. For a right hand club the screw-thread 14 is left-handed, and for a left hand club the screw-thread is right-handed. The screw thread 14 is preferably 90 of V-shape with its convolutions spaced apart, so as to readily screw into the wood, as well as to provide sufficient width of the screw-thread of the head so as to obtain 95 the firm anchoring of the shaft in the head without danger of the screw-thread of the head tearing loose. It will also be noted that the sleeve 12 being tapered will wedge tighter in the head the further the head and shaft are screwed together.

100 Having thus described the invention, what is claimed as new is:—

1. A golf club comprising a head having a shank provided with a tapered socket, a tubular metal shaft, and a metal sleeve cast on the lower terminal of said shaft, said sleeve being tapered downwardly to wedge tightly into said socket and having screw-threads engaging the head.

110 2. A golf club comprising a head having a shank provided with a tapered socket, a tubular metal shaft, and a metal sleeve cast

on the lower terminal of said shaft, said sleeve being tapered downwardly to wedge tightly into said socket and having a screw-thread at its lower end engaging the head,
5 the upper portion of the sleeve projecting from the shank.

3. A golf club comprising a head having a shank provided with a tapered socket, a tubular metal shaft, and a metal sleeve cast

on the lower terminal of the shaft and screw-threaded in said socket, said sleeve being tapered downwardly to wedge tightly into said socket, the screw-threads extending in a direction to tighten the head on the sleeve due to impact of the head with a ball. 10 15

In testimony whereof I hereunto affix my signature.

FRANK L. SLAZENGER.
